UNITED STATES PATENT OFFICE.

LAFAYETTE HARDWICK CALDWELL, OF CHATTANOOGA, TENNESSEE.

INSERT FOR CASTINGS.

Application filed September 10, 1928. Serial No. 305,092.

This invention relates to improvements in the art of casting metals and it consists of the constructions, combinations and arrangements herein described and claimed.

5 One of the objects of the invention is to join two members (castings in the instant case) without either drilling into or through either member for the reception of the securing bolt, the arrangement being such that the 10 bolt will be mounted on the inside of the members and not visible from the outside thus avoiding marring the outer appearance.

Another object of the invention is to employ an insert for the purpose of forming a 15 recess which will securely hold the head of a bolt, in which connection it serves as the foundation for a crib from which the bolt extends when inserted in place.

Another object of the invention is to provide an insert which is of a configuration particularly suited to serve the purpose of a 20 foundation for a crib in castings.

A further object of the invention is to provide a fastening means for castings and the 25 like, according to which the drilling and tapping as well as molding of holes and the use of cotter pins are dispensed with.

Other objects and advantages appear in 30 the following specification reference being had to the accompanying drawing, in which

Figure 1 is a side elevation of a stove leg, the improved casting structure being shown,

Figure 2 is a detail section taken on the line 2—2 of Figure 1,

35 Figure 3 is a cross section of a portion of the stove leg as well as a portion of the base strip to which it is attached by means of the improved connection,

Figure 4 is a detail vertical section taken 40 on the line 4—4 of Figure 1,

Figure 5 is a plan view of the insert blank prior to being bent into shape,

Figure 6 is a plan view of the completed 45 insert,

Figure 7 is an edge view as seen in the direction of the arrow in Figure 6,

Figure 8 is an inverted plan view of the 50 insert,

Figure 9 is a perspective view of the insert.

55 As has been indicated by the statement in one of the objects of the invention, the purpose of the latter is to so join two members that the means by which the joint is made will not be visible from the outside and, moreover, the joint will be so firm that the members will not loosen up in ordinary use and thus

render the structure unsteady. The improved connection is primarily intended for use in joining a leg with the base strip of a stove, but the illustration herein of that purpose is not to be regarded as a limitation upon the use of the invention for the principles of the invention will be used in other parts of a stove and in connecting members other than stove castings. 60

It is usual in the manufacture of stoves to either drill a hole in one member and tap it for the reception of a bolt which is fitted through a hole in another member to be secured. It is also usual to secure stove members by means of cotter pins. The first mode of connection consumes considerable time and is expensive, while the second mode results in an unsteady connection. It is not unusual to form a hole clear through a stove part and to 75 introduce the bolt from the outside so that the head of the bolt shows. This mars the appearance of the structure.

According to the invention the head of the securing bolt is held more firmly than if it were screwed into a tapped hole, and it has the same advantage of secreting the bolt so that the connecting means is not visible on the outside of the stove. The purpose is carried out by forming what is herein known as a 85 crib on the inside of one of a pair of members to be joined. The foundation of this crib is an insert which is of a form particularly suited to the purpose.

Reference is made to the drawing. The 90 particular members to be joined comprise the leg 1 and base strip 2 of a stove. These members are castings. The stove leg has a set of lugs 3 (Fig. 1) with which a tongue 4 on the base strip 2 coacts in producing a snug tentative fit. This fit is later made permanent by the use of a stove bolt 5 and nut 6. The bolt passes through a hole 7 in the tongue 4. The tongue is so offset from the base strip that it defines a cavity which becomes a chamber 8 100 when the tongue is applied to the inner side of the stove leg.

The manner in which the head 9 of the stove bolt 5 is held securely in a secreted position is as follows: A crib 10 has a recess 11 which is wedge shaped in the longitudinal direction of the stove leg (Figs. 1 and 4), and a slot 12 which opens at the inner side of the crib both to admit the head 9 to the recess and to receive the bolt 5. The bolt is inserted head down, 110 that is to say with the head next to the inside of the leg 1, the threaded part of the bolt ex-

tending straight out through the slot 12, in position to receive the tongue 4 of the base strip 2. Having made this connection, the nut 6 is screwed down tight.

5 A wall 13 (Figs. 1 and 2) closes one side of the recess 11. It is adjacent to this wall that the slot 12 ends. The inner surface of the wall is bevelled to match the shape of the head 9 (Fig. 3). The particular disposition of the 10 recess 11 and slot 12, described above, is not necessarily adhered to because it is conceivable that the crib 10 may be molded onto the stove leg 1 in other positions. For instance, the slot 12 may be made to open upwards in- 15 stead of to the side. Reverting to the connection of the members 1 and 2 at the bolt 5, the screwing down of the nut 6 will produce an outward thrust of the head 9 against the bevelled sides of the recess 11. The connec- 20 tion will be very tight, and in ordinary use the leg 1 will never loosen.

The mode in which the crib 10 is formed so that the walls of the recess 1 will be smooth and both accurately and uniformly bevelled 25 to make the best possible contact with the head 9 is as follows: An insert 14 (Figs. 5 to 9) is used for the purpose. This insert comprises the foundation upon which the crib 10 is molded. The insert will be incorporated in 30 the crib, and its form is such that sharp corners are defined particularly at 15, 16 and 17, although sharp corners are not essential to a properly molded recess. It is possible to make the corners round with the same effect 35 as far as the recess is concerned.

Figures 6 to 9 illustrate the insert in its bent up form, that is to say, the form it assumes when ready to be incorporated in the casting. It comprises top and side flanges 18 40 and 19 which ultimately become parts of the top of the crib 10 and of the wall 13. The longitudinal edge of the side flanges 19 has an attached clip 20 of an exaggerated U- 45 shape. This clip will be dished in the formation of the insert, as shown in Figure 9, the angle of the dish being approximately 45° to suit the inclination of the sides of the head 9.

The inner edge 21 of the clip matches a 50 slot 22 in the top flange 18 when the clip is bent over into position. At the same time the extreme edges 23 of the clip will match one edge of a pair of triangular tangs 24 formed on the edge of the flange 18 opposite to that 55 side from which the flange 19 is bent. The tangs 24 are bent up to match the edges 23 (Fig. 9).

In use the insert 14 will be disposed face down in respect to the back of the leg 1. It 60 will be incorporated in the mold. Upon cast-

ing the metal the insert will become incorporated in the leg 1, it having been pointed out that by the use of the insert the crib 10 will be formed as nearly perfect as possible, but what is most important, the use of the 65 insert makes it possible to accurately form the recess 11 so that the stove bolt 5 can be fitted in a concealed position upon the leg. The ultimate connection of the second member 70 of the stove with the leg will be as secure and more so as the best drilled and tapped joint.

In conclusion reference is made to Figure 5. This illustrates the stamped block. The 75 insert will be composed of a light metal, usually tin. It is deemed unnecessary to describe how the insert is bent into the final form in Figure 9 because this is a matter which has no direct bearing on the invention. The insert is bent into the ultimate shape shown in Figure 9, and this article is incorporated in the casting, whether that be a stove or some other part, in the manner already brought out.

While the construction and arrangement of the improved art of casting metals is that of 85 a generally preferred form, obviously modifications and changes may be made without departing from the spirit of the invention or the scope of the claims.

I claim:—

1. An insert which has a flange with an opening, and a clip which is dished and has one edge following said opening.

2. An insert which has a flange with a slot that opens at one edge of the flange, and a clip 95 of a substantial U-shape, having one edge following the slot and stopping at that edge of the flange where the slot opens, said clip being dished to provide the wall of a bevelled recess.

3. An insert having a top flange, a side flange along one side of the top flange said top flange having a slot opening at the opposite side which opposite side has a pair of triangular tangs adjacent to said slot, and a 105 clip attached to the side flange, said clip having inner edges following the slot and having the extreme edges coinciding with one edge of the tangs, said clip being dished to agree with said side edges of the tangs. 110

4. An insert comprising connected flanges standing at angles to each other, one of the flanges having an opening, and a clip depending from the other flange and following the contour of the opening. 115

Signed at Chattanooga, in the county of Hamilton and State of Tennessee, this 29th day of August, A. D. 1928.

LAFAYETTE HARDWICK CALDWELL.
